UNITED STATES PATENT OFFICE.

ALEXANDER T. BROWN, OF SYRACUSE, NEW YORK.

TYPE-WRITING MACHINE.

SPECIFICATION forming part of Letters Patent No. 794,923, dated July 18, 1905.

Application filed October 16, 1902. Serial No. 127,545.

To all whom it may concern:

Be it known that I, ALEXANDER T. BROWN, a citizen of the United States, and a resident of Syracuse, in the county of Onondaga and State of New York, have invented certain new and useful Improvements in Type-Writing Machines, of which the following is a specification.

My invention relates to ribbon mechanism for type-writing machines, and more particularly to mechanism for automatically reversing the direction of feed of the ribbon when an end thereof is approached; and the main object of the invention is to provide comparatively simple mechanism of the character specified which is reliable and efficient in operation.

To these and other ends, which will hereinafter appear, my invention consists in the features of construction, arrangements of parts, and combinations of devices to be hereinafter described, and particularly pointed out in the appended claims.

In the accompanying drawings, wherein like reference characters indicate like parts in the various views, Figure 1 is a vertical front-to-rear sectional view of one form of type-writing machine embodying my invention. Fig. 2 is an enlarged vertical transverse sectional view of the machine above the base and with parts omitted and parts broken away, the view being taken at the front of the machine. Fig. 3 is an enlarged detail side view, partly in section and with parts broken away, of a portion of the ribbon mechanism, the view illustrating the positions of the parts when engagement is effected to afford a reversal in the direction of the feed of the ribbon. Fig. 4 is a like view of the same, showing the different disposition of the parts, or that attained when reversal in the direction of the feed of the ribbon is about to take place. Fig. 5 is a view corresponding to Fig. 4, except that it shows the disposition of the parts after a reversal in the direction of the feed has taken place. Fig. 6 is an enlarged detail perspective view, with parts in section and parts broken away, of a portion of the ribbon-reversing mechanism. Fig. 7 is an enlarged detail perspective view

of one of the ribbon-reversing devices to be hereinafter described. Fig. 8 is a detail transverse sectional view of a portion of the reversing mechanism, the view being taken on the line *xx* of Fig. 11. Fig. 9 is a vertical longitudinal sectional view of a portion of the ribbon mechanism, the section being taken on the line *yy* of Fig. 11. Fig. 10 is an enlarged detail perspective view of a portion of the mechanism to be hereinafter described. Fig. 11 is a fragmentary plan view of a portion of the ribbon mechanism with parts broken away and parts in section. Fig. 12 is a detail plan view of the ribbon guide or vibrator. Figs. 13, 14, and 15 are central vertical sectional views of the same, showing three different angles that the vibrator is adapted to assume.

In the various views parts have been omitted and parts broken away to better illustrate other features of the construction.

I have illustrated my invention applied to a front-strike type-writing machine, though it should be understood that the invention or any of the separate features thereof may be applied to other characters of writing-machines.

The frame of the machine is made up of a base 1 and a frame 2, which is supported on the base, and this frame or casting 2 supports the carriage 3 and various working parts of the machine. The frame 2 is provided with rails 4, that extend from side to side of the machine and are grooved on their inner faces for the reception of antifriction-balls 5, that are likewise received in companion grooves 6 in the cross-rails 7 of the carriage. In this manner the carriage is supported to travel from side to side of the machine. The base 1 has depending rods 8, which, together with the supporting-plate 9, constitute means for supporting a platform 10 to the base. This platform is provided with upwardly-extending lugs or studs 11, that are recessed at 12 for the reception of pivots 13, projecting laterally from key-levers 14, which have finger-keys 15 at their forward ends and are each provided with an upwardly-extending arm 16, that extends into the path of and is adapted to bear upon a pad 17 of a segmental universal bar 18, provided with upwardly-extending

arms 19, connected thereto at or near its ends. These arms are pivoted at their upper ends 20 to forwardly-extending bracket-arms 21, which are supported upon a type-bar segment 22, the forward ends of the bracket-arms being connected to a segmental support 23, provided with a pad 24, which constitutes a support against which the forward ends of the type-bars 25 normally rest. These type-bars 10 are each mounted in a hanger 26, secured by a screw 27 to the type-bar segment 22, and each type-bar is connected by a link 28 to the upwardly-extending arm 16 of the associated key-lever, each type-action being restored to 15 its normal position by a spring 14^a. The arms 19, which support the universal bar, are connected by rearwardly-extending links 29 to crank-arms 30, depending from a rock-shaft 31, which extends from side to side of the machine, as illustrated in Fig. 2, and is supported by screw-bearings 32, that take in threaded openings in the sides of the frame 2 and bear at their inner coned ends in openings in the rock-shaft 31. A coiled spring 33 surrounds 20 the rock-shaft 31 and is connected at one end 34 to one of the crank-arms 30 and at its opposite end 35 to one of the cross-rails 4. Rigid feed-dogs 36 are formed in one piece with or are connected to a sleeve 37, secured by a screw 30^a 37^a to the rock-shaft 31, and the dogs coöperate with an escapement-wheel 38, that is rigidly secured to a shaft 39, supported at one end in an adjustable screw-bearing 40, received in the rear portion of the frame 2, and the opposite 35 end of the shaft is reduced at 41 and is received in a bearing in the forward portion of the frame 2. Surrounding the shaft 39 is a loosely-mounted sleeve 42, that is provided with teeth 43 on one end thereof, which constitutes one 40 member of a two-part clutch. This sleeve is likewise provided with a pinion 44, which meshes with a gear-wheel 45. A suitable spring (not shown) is interposed between the sleeve 42 and the escapement-wheel 38 and tends to normally maintain the teeth 43 in 45 engagement with the coöperating teeth of the other clutch-section, which latter is formed as a part of a worm 46, secured to the shaft 39. The disposition of the parts is such that 50 the sleeve 42 may be moved longitudinally upon the shaft 39 by any suitable means against the tension of its spring to effect a disengagement of the clutch members without moving the pinion 44 out of mesh with its 55 coöperating gear 45 and in order that the escapement mechanism and ribbon mechanism may be entirely disconnected from the carriage and may be maintained at rest during the return movements of the carriage to the 60 right, as will hereinafter more clearly appear.

The gear 45 meshes with a rack 46, that extends longitudinally of the carriage and is secured to the under side of one of the cross-rails 7, and constant mesh is maintained between the gear and the rack 46. Connected

to the gear 45 is a bevel-pinion 47, which meshes with a coöperating bevel-pinion 48, having its collar 49 secured to a shaft 50 by a set-screw 51. The shaft 50 is extended beyond the face of the bevel-gear 48, where it 70 is received in suitable bearings carried by the frame 2, whereas the opposite end of said shaft is received within a screw-bearing 52, that takes in a threaded opening in the side wall of the frame 2. The shaft 50 likewise 75 has a pinion 53 secured thereto by a screw 54, and a segmental rack 55 meshes with this pinion, the rack being pivoted at 56 to a forwardly-extending bracket-arm 57, secured to the frame 2 of the machine. The segmental 80 rack 55 has a handle 58, which extends forwardly of the pivot in order that the rack and the parts controlled thereby may be actuated by hand, as will hereinafter more clearly appear. The carrier for the segmental rack 55 85 is provided with a plain-faced segmental portion 59, against which a strap 60 is adapted to bear, one end of the strap being secured to the carrier of the segmental rack at 61, whereas the opposite end of said strap or 90 band is connected at 62 to a contractile spring 63, that has its opposite end connected at 64 to a strap or band 65. The forward end of the strap 65 is secured by a screw 66 to a block 67, that is tapped to receive a threaded 95 rod 68, the rear end of which is received within a bearing 69, formed in the base of the machine, whereas the forward head of said rod extends through the front of the base and is seated in a depression therein and is 100 provided with a notch to afford a turning of the rod or spindle by a screw-driver to effect an adjustment of the tension of the spring 63.

From the foregoing description it will be understood that the tension of the spring 63 105 is exerted upon the segmental rack 55 and through the pinions 53, 48, and 47 and through the gear 45 to the rack 46 to effect a movement of the carriage from right to left or in the direction of its feed when the feed-dogs 110 36 are vibrated to afford a movement of the escapement-wheel. The disposition of the parts is such that the handle 58 will be in the uppermost position when the carriage has completed its travel toward the left. A depression of the handle will therefore move the carriage through the segmental rack 55 and the intermediate connections back to the initial position or to the extreme right. It will be understood, therefore, that the spring 63 115 constitutes a carriage-spring and that the tension of the spring is increased when the handle 58 is depressed to move the carriage to the right.

The platen 70 is supported in a platen-frame 120 71 upon links 72, which are pivoted to the end plates of the carriage at 73. The platen-frame is pivoted at 75 to crank-arms 74, that extend forwardly and upwardly from a rock-shaft 76, which is supported in bearings 77, that 125 130

extend rearwardly from the forward cross bar or rail 7 of the carriage. The rock-shaft 76 likewise has a centrally - located depending arm 78, which is provided at its lower end 5 with an antifriction-roller 79, bearing upon a plate 80, that extends from side to side of the machine and is connected to or formed integral with the rock-shaft 81, that is supported in bearings in the ends of the frame 2. This so-called "rock-shaft" 81 likewise has a forwardly - projecting crank - arm 82 secured thereto and at the forward ends of which is pivoted at 83 a downwardly-extending link 84, pivoted at its lower end 85 to a lever 86, the lever being pivoted at 87 to a post 88, that extends upwardly from the platform 10. The forward end of the lever 86 is provided with a key 89, by means of which the lever can be actuated to effect a movement of the platen through the intermediate connections, platen-frame, and key-lever, thereby shifting the platen from the lower to the upper case position, the weight of the platen and its associated parts being sufficient to move the platen 25 to the lowermost position. This movement of the platen in a direction transverse to its length enables it to be brought into position to receive an impact of either the inner or outer types on the type-bars.

The rock-shaft 31 for the feed-dogs is provided with a sleeve 90, which is secured thereto by a pin 91, that extends through the sleeve and shaft. This sleeve is provided with an abutment or stop 92, (see Figs. 13, 14, and 15,) 30 which extends from one edge thereof and in the direction of the length of the platen and co-operates with the stop-faces 93 and 94 from one end of the sleeve-like bearing portion 95 of the ribbon-vibrator. This sleeve 95 surrounds the shaft 31 and is provided with forwardly - extending arms 96, that carry antifriction rollers or pulleys 97 between the ends thereof and on a pivot 97^a, that extends from one arm to the other. A frame 98 has arms 45 99, that are riveted at 100 to the supporting arms 96, and extending inwardly from the arms 99 and toward each other are fingers 101, as represented in Fig. 12. The upper bearing or terminal portion 102 of the ribbon vibrator or guide is secured to the frame 98 at 50 103 and is bent at an angle thereto, as represented in Fig. 1. This ribbon-guiding portion 102 is provided with a central division-piece 104, that is formed into a downwardly-extending hook and from which oppositely-sloping guide-walls 105 extend. These sloping walls are paralleled by guide-fingers 106, each of which extends throughout a portion 55 of the length of its associated guide wall or edge.

The shaft 31 has a collar or flange 107 secured thereto, and one end of a coiled spring 108, which surrounds the shaft, is secured to this collar, whereas the opposite end of said 60 spring is secured to the carrier or sleeve 95 of

the vibrator and tends to normally maintain the vibrator in the position shown in Fig. 13—that is to say, the tension of the spring 108 is exerted to maintain the abutment 94 on the sleeve 95 in contact with the abutment 92, 70 Fig. 13, on the collar 90, which is secured to the rock-shaft, and this relative disposition of the ribbon-vibrator and rock-shaft 31 is maintained under normal conditions. The ribbon 109 extends from one ribbon-spool, over one 75 of the guide-rollers 97 on the ribbon-vibrator, between the associated guide-finger 101 and the frame 98 of the vibrator, thence over one of the sloping walls 105, and between it and the associated guide-finger 106, where it makes 80 a turn and passes over and turns on the opposite wall 105 and back under the other finger 101, thence over the associated roller 97, and back to the other ribbon-spool, so that throughout the entire extent, except where the ribbon 85 makes a turn upon the bearing portion 102 of the ribbon-vibrator, the ribbon is maintained in substantially parallel lengths. The ribbon in passing from one sloping wall 105 to the other passes under the hooked portion 90 of the division-piece 104, which prevents the ribbon from being accidentally displaced from the outer end of the ribbon-vibrator. A depression of a finger-key will force the associated type-bar to the printing-point, as indicated in dotted lines in Fig. 1, thereby bringing the arm 16 of the associated key-lever into contact with the universal bar, thus moving it toward the front of the machine to the dotted-line position, and the effect of which is to 100 turn the rock-shaft 31, thereby affording a movement of the feed-dogs toward the front of the machine. This same movement of the rock-shaft 31 is effective to move the ribbon-vibrator from the position shown in full to 105 that indicated in dotted lines in Fig. 1, and the ribbon will be brought into the path of the type before it reaches the printing-point. When the finger-key is released, the parts 110 will be restored to the normal position. (Represented in full lines in Fig. 1 and indicated in Fig. 14.) Should the operator desire to move the ribbon-vibrator to a further extent from the platen, in order that erasures or corrections may be made with greater facility and 115 without removing the paper from the machine or turning the platen, it is merely necessary to depress the ribbon-vibrator, and it may be moved around the shaft 31 from the normal position (indicated in Fig. 14) to that indicated 120 in Fig. 15. At this time the rock-shaft 31 is maintained at rest and the ribbon-vibrator is merely moved against the tension of the spring 108, and the relative movement of the ribbon-vibrator to the rock-shaft 31 is arrested by the 125 abutment 93 on the vibrator carrier or sleeve coming into contact with the abutment 92, secured to the rock-shaft, and which at this time is maintained fixed relative to the vibrator. When the vibrator is released, the tension of 130

- the spring 108 will force it back to the normal position, where it is arrested by the abutment 94 coming into contact with the relatively fixed abutment 92 on the rock-shaft.
- 5 The next depression of the finger-key will cause the vibrator to move from the full to the dotted line position in the usual manner, the parts being maintained in a fixed relation by the spring 108.
- 10 I will next describe the ribbon-feed mechanism and the means by which the direction of the feed of the ribbon is automatically reversed.
- The worm 46, hereinbefore described, co-15 operates with a worm-wheel 110, that carries a pawl 111, pivoted thereto at 112, the pawl being normally maintained in engagement with a coöperating ratchet-wheel 113 by a spring 114, secured at 115 to the worm-wheel 20 and bearing at its free end against the pawl. The ratchet-wheel 113 has a sleeve 113^a, which is secured by a screw 116 (see Fig. 9) to a shaft 117, received in bearings in the frame 2 of the machine. One of these bearings is formed by 25 an upwardly-extending bracket 118, whereas the opposite bearing is formed by a screw-collar 119, received and adjustable in a threaded opening in the frame 2. The worm-wheel 110 is loosely mounted on the shaft 117 and is held 30 against longitudinal displacement thereon by the ratchet-wheel 113 on one side and a collar 120 on the other. This collar or flange projects from a sleeve 121, that surrounds the shaft, and is secured thereto by a screw 122, and interposed between the shaft and the sleeve are 35 spring-arms 123, which terminate in bearings 124 for the pivots of rollers or detents 125. The shaft 117 has a groove extending throughout or substantially throughout the length 40 thereof for the reception of a bar 126, that turns with the shaft, but is adapted to slide longitudinally in its groove independently of the shaft. The outer end of this bar terminates in a threaded portion 127, as shown in dotted lines in Fig. 9, and a nut 128, having a knurled head, is adapted to be received on the threaded end of the bar and affords hand-operated means by which the bar may be moved longitudinally when desired and likewise constitutes a collar which limits the movements of 50 the bar in one direction by bearing against the sleeve 129, from which projects a crank-arm 130, provided with a handle 131. The crank-arm, sleeve, and handle are secured to 55 the shaft 117 by a screw 132, so that the shaft, together with the parts carried thereby, may be rotated by hand when desired, it being understood that the handle and thumb-nut 128 project beyond one side of the machine where 60 they are accessible to the operator. The bar 126, hereinbefore referred to, is provided with lateral projections or cams 133, that coöperate with the detents or rollers 125, which tend to move the bar longitudinally in either direction when the crowns 134 of the cams pass
- the centers of the rollers in either one direction or the other, and the tension of the springs 123 tends to maintain the bar in the position to which it is shifted after a complete movement thereof in either direction has taken 70 place by forcing the rollers against the sides of the cams, as indicated in Fig. 9. The bar 126 is apertured or slotted at 135 for the reception of a stem 136, that projects laterally from a double locking or engaging pawl or 75 clutch member 137, each end of the pawl being provided with an engaging nose 138, as represented in Fig. 11. The pawl 137 is in the nature of a slide, which is received within a groove 139 in a sleeve 140, which surrounds 80 the shaft 117 and has a transverse opening 141, through which the stem 136 of the pawl projects. The disposition of the parts is such that an independent movement of the bar 126 longitudinally of the shaft 117 may take place 85 before such movement is transmitted to the pawl 137. The sleeve 140 is secured to the shaft by a headed screw 142, (see Fig. 9,) that is entered through an opening 143 in the core of one of the ribbon-spools and 90 takes in threaded openings in the sleeve and shaft to unite the sleeve to the shaft. Surrounding the sleeve 140 are two ribbon-spools 144 and 145, which are adapted to turn thereon, the ribbon-spools being prevented from 95 moving longitudinally on the shaft by cams 146 and 147 on opposite sides thereof, and which are secured to the shaft by screws 148, that extend through threaded openings in the sleeve and bear at their inner ends against the 100 shaft. The outer head of each ribbon-spool has secured near the core thereof a disk provided with a circular series of inwardly-extending ratchet-teeth 149, that project toward the teeth of the other spool, as indicated in 105 Fig. 11, and which are adapted to coöperate with the double pawl 137. Thus when the pawl receives the limit of its movement to the right in Fig. 11 it engages the teeth 149 of the ribbon-spool 145 and causes said spool to 110 rotate with the shaft, whereas a movement of the pawl to the left disengages the teeth on the ribbon-spool 145 and throws the pawl into engagement with the teeth 149 on the ribbon-spool 144.
- 115 Mounted on the shaft 117 and upon opposite sides of the ribbon-spools are so-called "reversing devices" 150 and 151, each of which consists of a sleeve surrounding the shaft and which has a cam opening or groove 120 152 therein, these cams extending in opposite directions, as represented in Figs. 9 and 11. These devices are loosely mounted on the shaft and each of them is provided with laterally-extending fingers or abutments 153, which 125 are preferably diametrically opposite each other, as represented in Fig. 7. The cams 146 and 147, hereinbefore described, have the general elliptical shape, so that they each constitute a peripheral cam with diametrically 130

opposite low portions 154, that permit the fingers 153 of the associated reversing device to project beyond the edge thereof, whereas the highest portions 155 of each cam are so related to the fingers 153 of the associated reversing device that when the longitudinal axis of the cam is brought into alignment with the fingers, as represented in Fig. 5, the outer ends of said fingers will be coincident with or lower than the peripheral face of the co-operating cam. The bar 126 is provided with studs 156, which extend into the cam-grooves 152 in the reversing devices, as represented in Figs. 9 and 11, and a relative turning movement of the shaft and pins 156 of either of the reversing devices will cause a longitudinal movement of the bar 126 by the co-operation of the cams with the associated pins 156 extending from the bar, the direction of movement depending upon which pin 156 and its associated cam receives a relative movement. Thus if the reversing device 151 is arrested while the shaft 117, with the bar 126 and its pins 156, continues to rotate the cam of the device 151 will cause the bar 126 to be moved toward the left, and after the detent-rollers 125 pass over the crowns of the cams 133 they tend to assure the complete movement of the bar 126 to the left. On the other hand, if the reversing device 150 is arrested, so that there is a relative rotary movement between the shaft 117, bar 126, with the pins 156 carried thereby, and said reversing device, then the bar 126 will be moved longitudinally in its groove toward the right. As heretofore explained, the longitudinal movement of the bar controls the pawl 137. Thus after a limited independent movement of the bar in either direction an end wall of the slot 135 in the bar will contact with the finger 136 of the pawl and move it out of engagement with the teeth 149 of one ribbon-spool and into engagement with the teeth of the other ribbon-spool. The engaged ribbon-spool will be positively locked to the shaft and rotated therewith, whereas the released ribbon-spool will rotate freely on its bearing and be turned by the pull of the ribbon thereon in an opposite direction from that of the positively-driven spool, thus winding the ribbon on one spool and unwinding from the other.

In order to automatically arrest either of the reversing devices 150 and 151 when an end of the ribbon is approached, I have provided independently-operable automatically-actuated devices, which will now be described. These devices consist of two sets of arms, one for each ribbon-spool. Thus an arm or bearing-piece 157 is rigidly secured to a sleeve 158, which turns freely upon a fixed shaft 158^a, that is mounted in bearings 159 on the frame 2 of the machine. This bearing-arm 157 is adapted to vibrate between the flanges or heads of its associated ribbon-spool and to bear upon the outer surfaces of the ribbon, as

represented in Figs. 3, 4, and 5. An associated stop-arm 160 is secured by a screw 161 to a weight 162, that is rigidly secured to the sleeve 158 and tends to maintain the bearing piece or arm 157 in contact with the surface 70 of the ribbon. This stop-arm 160 projects to one side of its associated ribbon-spool, as represented in Fig. 2, and is adapted to bear at its free end upon the cam 146 when the ribbon is sufficiently unwound from the associated ribbon-spool to permit it to do so, as represented in Figs. 3, 4, and 5. A like set of arms are employed for the ribbon-spool 145. Thus an arm or bearing-piece 157^a is adapted to project between the flanges of the ribbon-spool 145 and to bear upon an outer surface of the ribbon, and this arm is connected to a sleeve 158^b, which turns freely on the shaft 158^a and is provided with a weighted portion 162, to which an arm or stop 160^a is secured, the latter projecting to one side of its associated ribbon-spool and being adapted to bear at its free ends upon the associated cam 147 when the ribbon on the spool 145 is sufficiently unwound to permit it to do so. 90

It should be understood that the fingers 153, which project from the reversing devices, extend at right angles to each other—that is to say, the fingers of one reversing device extend at right angles to the fingers of the other reversing device—and this relative position of the fingers is maintained at all times irrespective of the fact that the devices are loosely mounted upon the rock-shaft and that the latter has a movement under certain conditions 100 relative of said devices.

From an examination of Figs. 2, 3, and 4 it will be understood that the disposition of the parts is such that the ribbon is being unwound from the spool 144, whereas the spool 145 is rigidly connected to the shaft to rotate therewith in the direction of the arrow indicated at the spool 145 in Fig. 3, so that the ribbon is wound upon the spool 145. At this time the right-hand reversing device 151 has its fingers 153 extending beyond the periphery of the cam at the lowest portions thereof, and when the end of the ribbon on the spool 144 is approached or the ribbon is sufficiently unwound the stop-arm 160 is permitted to extend 110 into the path of one of the fingers 153 on the reversing device 151, as indicated in Fig. 3, thus arresting the movement thereof with the shaft 117. The continued rotation of the shaft 117 for a quarter-turn turns the associated cam 146, which is secured to the shaft, from the position indicated in Fig. 3 to that shown in Fig. 4. The cam during this movement, bearing, as it does, on the free end of the stop-arm 160, raises it and brings one of the highest portions 155 of the cam opposite the engaged finger, so as to disconnect the stop-arm 160 from the finger 153 on the reversing device, as indicated in Fig. 4, which shows the positions of the parts just before the stop-arm is 120 125 130

disengaged from the finger. The effect of this operation is to afford a quarter-turn of the shaft with reference to the reversing device 151, which relative movement of the parts is effective to move the bar 126 toward the left, thereby disengaging the pawl 137 from the spool 145 and at the same time forcing the pawl into engagement with the teeth on the spool 144. This releases the spool 145 and locks the spool 144 to the shaft, so that the ribbon-spools turn in the opposite directions from those in which they turned before the shifting of the bar 126. Fig. 5 represents the disposition of the parts after the reversing operation has taken place, and it will be observed that at this time the fingers 153 on the reversing device 151 extend in the direction of the longitudinal axis of the cam, and the free edge of the stop-arm 160, bearing on the periphery of the cam, will be prevented from engaging the fingers. The ribbon continues winding on the spool 144 during the operation of the machine until it is sufficiently unwound from the spool 145 to enable the stop-arm 160^a to be brought into engagement with one of the fingers 153 of the reversing device 150, when said reversing device will be arrested by the stop-arm, which will effect a longitudinal movement of the bar 126 toward the right and a reversal in the direction of the feed of the ribbon will be automatically brought about in the manner heretofore described. It will be understood that when either reversing device is arrested by its associated stop-arm it will cause a longitudinal movement of the bar 126 and that this movement of the bar in either direction will cause the reversing device, which is maintained with its fingers 153 in the direction of the longitudinal axis of its associated cam, to be moved a quarter-turn by reason of the engagement between the cam-slot and pin 152 and 156, so that the fingers will extend at right angles to the length of the associated cam, where they are in a position to be engaged by the associated arresting or stop arm 160 or 160^a during further revolution of the shaft. It further follows that when the fingers 153 of one controlling or reversing device are at right angles to the length of the associated cam, as indicated in Fig. 3, the fingers 153 of the other reversing device will extend in the direction of the longitudinal axis of the associated cam, as represented in Fig. 5, this right-angular disposition of the fingers 153 on the two reversing devices being likewise indicated in Fig. 9. The effect of this operation is to automatically set the parts for the next reversing operation every time the parts are actuated to bring about a reversal in the direction of the feed of the ribbon. Should the operator desire at any time to effect a reversal in the direction of the feed, it is merely necessary to move the bar 126 in a longitudinal direction by push-

ing it in or pulling it out through the thumb-nut or knurled head 128. It will likewise be seen that the operator may at any time wind the ribbon from one spool to another by turning the shaft 117 through the handle 131, the spool on which the ribbon is wound being determined by the disposition of the rod 126, which may be moved in the manner described.

In the operation of the machine an actuation of the finger-keys will afford a movement of the carriage in the manner hereinbefore described through the spring 63 and the intermediate connections between said spring and the carriage. The effect of the movement of these parts is to turn the worm 46, thereby transmitting an intermittent rotary motion to the shaft 117. The intermittent rotation of the shaft 117 will cause the ribbon-spool connected thereto by the pawl 137 to be positively rotated in one direction, thus winding the ribbon thereon, whereas the other spool is turned in an opposite direction by the pull of the ribbon thereon, so that the power applied to move the carriage is effective to move the ribbon mechanism. As the ribbon is gradually unwound from one spool to another the bearing device of the spool from which the ribbon is unwound will eventually permit the associated stop-arm to be projected into the path of the fingers 153 on the associated reversing device. A further quarter-turn of the shaft will bring about the relative movement between the engaged reversing device and the shaft in the manner hereinbefore described. This relative movement between these parts is effective to move the bar 126 longitudinally of the shaft, thus throwing the pawl 137 out of engagement with the ribbon-spool, which is locked to rotate with the shaft, and throwing said pawl into engagement with the ribbon-spool from which the ribbon was being unwound.

Various changes may be made without departing from the spirit of my invention, and certain features thereof may be employed without the others.

Certain of the parts shown in the accompanying drawings are not claimed herewith, but are claimed in separate applications filed by me herewith or in an application filed by me on the 21st day of April, 1902, and bearing Serial No. 103,898.

What I claim as new, and desire to secure by Letters Patent, is—

1. In a type-writing machine, the combination of ribbon-spools, a device which normally revolves with the ribbon-spools, and automatically-actuated means for stopping said device when an end of the ribbon is approached and for reversing the direction of the feed of the ribbon.

2. In a type-writing machine, the combination of ribbon-spools, a part which normally rotates with said ribbon-spools, means for au-

tomatically arresting said part when an end of the ribbon is approached, and means controlled by said part and coöperating with both ribbon-spools for automatically effecting a 5 change in the direction of the feed of the ribbon.

3. In a type-writing machine, the combination of ribbon-spools, reversing devices, one for each spool and which normally rotate with 10 said ribbon-spools, independently actuated means associated with each spool for automatically arresting the associated reversing device when an end of the ribbon is approached, and means controlled by said reversing devices for automatically effecting a change in 15 the direction of the feed of the ribbon.

4. In a type-writing machine, the combination of ribbon-spools, reversing devices, one for each spool and which are adapted to normally rotate with the ribbon-spools, controlling devices, one for each spool and which are adapted to bear upon the surface of the ribbon on the spools and each adapted to automatically arrest its associated reversing device, and 25 means controlled by said reversing devices for effecting a change in the direction of the feed of the ribbon.

5. In a type-writing machine, the combination of ribbon-spools, reversing devices, one 30 for each spool and which are adapted normally to rotate with the ribbon-spools, controlling devices, one for each spool and which are adapted to bear upon the surface of the ribbon on the spools, and each adapted to automatically arrest its associated reversing device, means controlled by said reversing devices for 35 effecting a change in the direction of the feed of the ribbon, and means for automatically preventing the arrest of one reversing device 40 when the other is adapted to be arrested by its controlling device.

6. In a type-writing machine, the combination of a shaft, ribbon-spools mounted on said shaft, engaging means carried by said shaft and adapted to connect either spool to rotate 45 with the shaft, and means independent of the spool for automatically actuating said engaging means when an end of the ribbon is approached.

50 7. In a type-writing machine, the combination of a shaft, ribbon-spools mounted on said shaft, engaging means carried by said shaft and adapted to rotate therewith and to move independently thereof, to connect either spool 55 to rotate with the shaft, reversing means for automatically actuating said engaging means, and means controlled by the ribbon on each spool and brought into coöperation with the reversing means to afford an actuation thereof of when an end of the ribbon is approached.

8. In a type-writing machine, the combination of a shaft that is rotatable in but one direction, ribbon-spools loosely mounted on said shaft, and means operable independently of 65 any strain on the ribbon for automatically re-

leasing one spool and locking the other to the shaft when an end of the ribbon is approached.

9. In a type-writing machine, the combination of a shaft that is rotatable in but one direction, ribbon-spools loosely mounted on said shaft, means for locking either spool to rotate with the shaft, a reversing device that coöperates with the locking means and which normally rotates with the shaft, and means which are automatically actuated when an end of the 75 ribbon is approached, to arrest said reversing device and automatically effect an engagement of one spool with and a disengagement of the other spool from the shaft.

10. In a type-writing machine, the combination of ribbon-spools, a shaft therefor, a pawl which is adapted to engage either of said ribbon-spools to lock the engaged ribbon-spool to rotate with the shaft, and means operable independently of any strain on the ribbon for automatically shifting said pawl when an end of the 80 ribbon is approached.

11. In a type-writing machine, the combination of ribbon-spools, a shaft upon which both ribbon-spools are loosely mounted, a pawl 90 which is carried by said shaft and adapted to engage either of said ribbon-spools to lock the engaged ribbon-spool to rotate with the shaft, and means operable independently of any strain on the ribbon for automatically shifting said pawl when an end of the ribbon is approached, to disengage the pawl from one ribbon-spool and effect an engagement thereof with the other ribbon-spool.

12. In a type-writing machine, the combination of ribbon-spools, a shaft on which said spools are loosely mounted, a bar that rotates with said shaft and moves longitudinally thereof, means controlled by said bar for effecting a connection between either spool and the shaft and for simultaneously effecting a disconnection between the other spool and the shaft, and means for automatically effecting a longitudinal movement of the bar when an end of the 100 ribbon is approached.

13. In a type-writing machine, the combination of ribbon-spools, a shaft on which both ribbon-spools are loosely mounted, a bar that rotates with said shaft and moves longitudinally thereof, means controlled by said bar for effecting a connection between either spool and the shaft and for simultaneously effecting a disconnection between the other spool and the shaft, reversing devices that are adapted 105 to rotate with the shaft, and means for automatically arresting either of said reversing devices to effect a longitudinal movement of said bar when an end of the ribbon is approached.

14. In a type-writing machine, the combination of a shaft, means for rotating said shaft in one direction, ribbon-spools loosely mounted on said shaft, means carried by the shaft and movable independently thereof for effecting a connection between one spool and 115

the shaft and for simultaneously effecting a disconnection between the other spool and the shaft, and means adapted to bear upon the ribbon on the spools and controlled thereby for automatically affording a movement of said connecting means when an end of the ribbon is approached.

15. In a type-writing machine, the combination of a shaft, means for rotating said shaft, 10 ribbon-spools loosely mounted on said shaft, means carried by the shaft and movable independently thereof for effecting a connection between one spool and the shaft and for simultaneously effecting a disconnection between the other spool and the shaft, reversing means which are operatively connected to said connecting means and adapted to rotate with the shaft, and means associated with each ribbon-spool for automatically arresting 20 the reversing means when an end of the ribbon is approached, to afford an actuation of the connecting means and thus effect a reversal in the direction of the feed of the ribbon.

16. In a type-writing machine, the combination of a power-driven carriage, a shaft operatively connected to be turned by the power applied to the carriage, ribbon-spools loosely mounted on said shaft, connecting means for connecting either spool to the shaft when the other is disconnected therefrom, and means independent of the ribbon-spool for automatically actuating said connecting means when an end of the ribbon is approached.

17. In a type-writing machine, the combination of a power-driven carriage, a shaft operatively connected to be turned by the power applied to the carriage, ribbon-spools loosely mounted on said shaft, connecting means for connecting either spool to the shaft when the other is disconnected therefrom, and means that are adapted to bear upon the ribbon on the spools and automatically afford an actuation of the connecting means when an end of the ribbon is approached, to effect a change in 45 the direction of the feed of the ribbon.

18. In a type-writing machine, the combination of a power-driven carriage, a shaft operatively connected to be turned by the power applied to the carriage, ribbon-spools loosely 50 mounted on said shaft, connecting means which rotate with the shaft and move independently thereof, for connecting either spool to the shaft when the other is disconnected therefrom, and means operable independently of any strain on the ribbon for automatically effecting an independent movement of said connecting means when an end of the ribbon is approached, to reverse the direction of the feed of the ribbon.

60. 19. In a type-writing machine, the combination of a power-driven carriage, a shaft operatively connected to be turned by the power applied to the carriage, ribbon-spools loosely mounted on said shaft, connecting means for 65 connecting either spool to the shaft when the

other is disconnected therefrom, reversing means carried by and adapted to rotate with said shaft, and means for automatically arresting the reversing means when an end of the ribbon is approached, to afford an actuation of the connecting means and thus effect a reversal in the direction of the feed of the ribbon.

20. In a type-writing machine, the combination of a power-driven carriage, a shaft operatively connected to be turned by the power applied to the carriage, ribbon-spools loosely mounted on said shaft, connecting means for connecting either spool to the shaft when the other is disconnected therefrom, reversing devices carried by and adapted to rotate with said shaft and operatively connected to the connecting means, arresting means that are adapted to project into the path of said reversing devices to arrest the movement thereof with the shaft, and devices which are connected to the arresting means and bear upon the ribbon, to automatically afford a reversal in the direction of the feed of the ribbon when an end thereof is approached.

21. In a type-writing machine, the combination of a power-driven carriage, a shaft operatively connected to be turned in one direction by the power applied to the carriage, ribbon-spools loosely mounted on said shaft, a pawl that is carried by and rotates with said shaft and slides longitudinally thereof in a groove therein and which is adapted to connect either spool to the shaft when the other spool is disconnected therefrom, reversing devices carried by the shaft and adapted to rotate therewith, intermediate connections between said reversing devices and said pawl, independently-operable arresting devices that coöperate with said reversing devices to momentarily arrest the movement thereof, and means for automatically affording a movement of one of said arresting devices to the operative position when an end of the ribbon is approached.

22. In a type-writing machine, the combination of ribbon-spools, means for turning said ribbon-spools, means for connecting either spool to its turning means, and means for controlling the actuation of said connecting means, which controlling means comprises two independently-operable sets of arms, one set for each ribbon-spool, one arm of each set being adapted to bear on the ribbon on the associated spool and the other being adapted to project into the path of and to arrest the movement of a part which is connected to the connecting means, and thereby afford an automatic reversal in the feed of the ribbon.

23. In a type-writing machine, the combination of ribbon-spools, a shaft for turning said ribbon-spools, clutch mechanism for connecting either spool to its turning-shaft, and means for controlling the actuation of said clutch mechanism which controlling means com-

prises two independently-operable sets of arms, one set for each ribbon-spool, and the arms of each set being rigidly connected, one arm of each set being adapted to bear on the outer surface of the ribbon on the associated spool and the other arm being adapted to project into the path of and to coöperate with a part which is connected to the clutch mechanism to actuate it, and thereby afford an automatic reversal in the feed of the ribbon.

24. In a type-writing machine, the combination of ribbon-spools, means for connecting either spool to its actuating means when the other spool is disconnected therefrom, and controlling means for affording an automatic actuation of the connecting means to reverse the direction of the feed of the ribbon, which controlling means comprises reversing devices that rotate with the spools, means for automatically arresting the reversing devices, and means for automatically releasing the reversing devices after they are arrested.

25. In a type-writing machine, the combination of ribbon-spools, means for connecting either ribbon-spool with its driving means, automatically-actuated means for controlling the operation of said connecting means, which controlling means comprises a device that is automatically thrown into the path of movement of a part connected to the connecting means to arrest the movement of said part and thus afford a relative movement of the said part and the spools, thereby effecting a movement of the connecting means to disengage one spool from its driving means and connect the other spool thereto.

26. In a type-writing machine, the combination of ribbon-spools, means for connecting either ribbon-spool with its driving means, cams which are adapted to rotate in unison with the spools, and which control the said connecting means, and means for automatically arresting one of said cams when an end of the ribbon is approached.

27. In a type-writing machine, the combination of a shaft, means for rotating the shaft, ribbon-spools loosely mounted on said shaft, means for connecting either ribbon-spool with the shaft, cams which are adapted to rotate in unison with the shaft and which control the said connecting means, and means for automatically arresting one of said cams when an end of the ribbon is approached, to afford an actuation of the connecting means and thereby change the direction of the feed of the ribbon.

28. In a type-writing machine, the combination of a shaft, means for rotating said shaft, ribbon-spools loosely mounted on the shaft, a ratchet-wheel connected to each ribbon-spool, a pawl adapted to coöperate with the ratchet-wheel of either spool, cams which are connected to said pawl and are adapted to rotate with the shaft, and means for automatically arresting one of said cams when an end of the

ribbon is approached, to afford an actuation of the pawl and thereby change the direction of the feed of the ribbon.

29. In a type-writing machine, the combination of a shaft, means for rotating said shaft, ribbon-spools loosely mounted on the shaft, a ratchet-wheel connected to each ribbon-spool, a pawl which is mounted to slide on said shaft longitudinally thereof and is adapted to coöperate with ratchet-wheel of either spool, oppositely-disposed cams which are connected to said pawl and are adapted to rotate with the shaft, and means for automatically arresting one of said cams when an end of the ribbon is approached to afford a movement of the pawl longitudinally of the shaft and thereby disengage the pawl from the ratchet-wheel of one spool and engage it with the ratchet-wheel of the other spool, to change the direction of the feed of the ribbon.

30. In a type-writing machine, the combination of ribbon-spools, means for connecting either ribbon-spool with its driving means, cams which are adapted to rotate in unison with the spools and which control the said connecting means, means for automatically arresting one of said cams when an end of the ribbon is approached, and cams for automatically disengaging the arresting means from the first-mentioned cams.

31. In a type-writing machine, the combination of a shaft, means for rotating the shaft, ribbon-spools loosely mounted on said shaft, means for connecting either ribbon-spool with the shaft, cams which are adapted to rotate in unison with the shaft and which control the said connecting means, and means for automatically arresting one of said cams when an end of the ribbon is approached, to afford an actuation of the connecting means and thereby change the direction of the feed of the ribbon, and releasing-cams which are fixed to said shaft and are adapted to automatically disengage the arresting means from said first-mentioned cams.

32. In a type-writing machine, the combination of a shaft, means for rotating said shaft, ribbon-spools loosely mounted on the shaft, a ratchet-wheel connected to each ribbon-spool, a pawl which is mounted to slide on said shaft longitudinally thereof and is adapted to coöperate with ratchet-wheel of either spool, oppositely-disposed reversing-cams which are connected to said pawl and are adapted to rotate with the shaft, means for automatically arresting one of said reversing-cams when an end of the ribbon is approached, to afford a movement of the pawl longitudinally of the shaft and thereby disengage the pawl from the ratchet-wheel of one spool and engage it with the ratchet-wheel of the other spool, to change the direction of the feed of the ribbon, and disengaging-cams which are fixed to rotate with said shaft and are adapted to disengage the arresting means from the arrested

reversing-cam after a longitudinal shift of the pawl has been effected, to permit the previously-arrested reversing-cam to continue its movement with the shaft.

5 33. In a type-writing machine, the combination of ribbon-spools, driving means therefore, means for connecting either spool to its driving means, means for automatically shifting the connecting means when an end of the 10 ribbon is approached, by arresting a part which rotates with the driving means and which comprises arresting devices that are automatically moved to the operative position, and cams that move in unison with the 15 driving means, for effecting a disconnection of the arresting devices after the connecting means have been shifted.

34. In a type-writing machine, the combination of ribbon-spools, means for turning 20 either of said ribbon-spools, means for automatically reversing the direction of the feed of the ribbon by arresting a part which normally moves when the ribbon-spools are turned, and disengaging-cams which likewise 25 move when the ribbon-spools are turned and which are effective to disengage the arrested part and permit a continuation of the movement thereof.

35. In a type-writing machine, the combination of ribbon-spools, a shaft on which said 30 ribbon-spools are loosely mounted, means for engaging either ribbon-spool to lock it to rotate with said shaft, sleeves which surround said shaft, a cam-slot in each sleeve, and means 35 coöperating with said cam-slots and connected to the engaging means for effecting an operation thereof.

36. In a type-writing machine, the combination of ribbon-spools, a shaft on which said 40 ribbon-spools are loosely mounted, a groove in said shaft, means for engaging either ribbon-spool to lock it to rotate with said shaft, sleeves which surround said shaft, a cam-slot in each sleeve, a bar that moves in the groove 45 in said shaft, projections on said bar that cooperate with said cam-slots, and intermediate connections between said bar and the engaging means.

37. In a type-writing machine, the combination of ribbon-spools, a shaft on which said 50 ribbon-spools are loosely mounted, a groove in said shaft, means for engaging either ribbon-spool to lock it to rotate with said shaft, sleeves which surround and are loosely mounted on 55 said shaft, a cam-slot in each sleeve, and automatically-actuated means for arresting one of said sleeves when an end of the ribbon is approached.

38. In a type-writing machine, the combination of ribbon-spools, a shaft on which said 60 ribbon-spools are loosely mounted, a groove in said shaft, means for engaging either ribbon-spool to lock it to rotate with said shaft, sleeves which surround said shaft, and are loosely 65 mounted thereon, a cam-slot in each sleeve,

and automatically-actuated means for arresting one of said sleeves when an end of the ribbon is approached and hand-actuated means for affording a movement of said bar to effect a reversal in the direction of the feed of the 70 ribbon at will.

39. In a type-writing machine, the combination of ribbon-spools, a shaft on which said ribbon-spools are loosely mounted, a groove in said shaft, means for engaging either ribbon-spool to lock it to rotate with said shaft, sleeves which surround and are loosely mounted on said shaft, a cam-slot in each sleeve, automatically-actuated means for arresting 75 said sleeves when an end of the ribbon is one approached, to automatically reverse the direction of the feed of the ribbon, and a finger-piece connected to said bar and by means of which it may be moved by hand at will to reverse the direction of the feed of the ribbon. 80 85

40. In a type-writing machine, the combination of ribbon-spools, a shaft on which said spools are loosely mounted, means for automatically turning said shaft during the actuation of the machine, hand-operated means 90 which afford a turning of said shaft at will, means for engaging either ribbon-spool to lock it to rotate with said shaft, cams that are adapted to rotate with said shaft, intermediate connections between said cams and the engaging 95 means, means for automatically effecting a relative movement between the shaft and cams to automatically actuate the engaging means, and hand-operated means for affording a relative movement of said cams and shaft to 100 reverse the direction of the feed of the ribbon at will.

41. In a type-writing machine, the combination of ribbon-spools, a shaft on which said spools are loosely mounted, means for automatically turning said shaft during the actuation of the machine, hand-operated means 105 which afford a turning of said shaft at will, means for engaging either ribbon-spool to lock it to rotate with said shaft, cams that are 110 adapted to rotate with said shaft, a sliding bar carried by said shaft and which constitutes a connection between said cams and the engaging means, means for automatically effecting a sliding movement of said bar to automatically 115 actuate the engaging means, and hand-operated means for affording a sliding movement of said bar to reverse the direction of the feed of the ribbon at will.

42. In a type-writing machine, the combination of a shaft, means for automatically and intermittently rotating said shaft, ribbon-spools loosely mounted on said shaft, means for connecting either spool to rotate with the shaft, cams that are adapted to rotate with 125 said shaft, intermediate connections between said cams and said connecting means, hand-operated means for affording a movement of the connecting means, and means for automatically arresting either of said cams when 130

an end of the ribbon is approached, in order to effect a relative movement of the shaft and arrested cam and thus effect a movement of the connecting means to reverse the direction of the feed of the ribbon.

43. In a type-writing machine, the combination of a power-driven carriage, a shaft that is operatively connected to be driven by the power that moves the carriage, ribbon-spools loosely mounted on said shaft, means for connecting either spool to rotate with the shaft, reversing-cams that are adapted to rotate with said shaft, intermediate connections between the cams and the connecting means, and means controlled by the amount of ribbon on either spool for automatically effecting an arrest of one of said cams when an end of the ribbon is approached, whereby the movement of the shaft relative to the arrested cam will afford a movement of the connecting means and a reversal in the direction of the feed of the ribbon.

44. In a type-writing machine, the combination of a power-driven carriage, a shaft that is operatively connected to be driven by the power that moves the carriage, ribbon-spools loosely mounted on said shaft, means for connecting either spool to rotate with the shaft, reversing-cams that are adapted to rotate with said shaft, intermediate connections between the cams and the connecting means, means controlled by the amount of ribbon on either spool for automatically effecting an arrest of one of said cams when an end of the ribbon is approached, whereby the movement of the shaft relative to the arrested cam will afford a movement of the connecting means and a reversal in the direction of the feed of the ribbon, hand-operated means for moving said connecting means at will, and hand-operated means for turning said shaft.

45. In a type-writing machine, the combination of a power-driven carriage, escapement mechanism therefor, a shaft operatively connected to said escapement mechanism, ribbon-spools loosely mounted on said shaft, means carried by the shaft for connecting either ribbon-spool to rotate therewith, sleeves that are loosely mounted on said shaft and are adapted to rotate therewith, cams on said sleeves, abutments or fingers carried by said sleeves, intermediate connections between the sleeves and said connecting means, means adapted to automatically drop into the path of the fingers on one of said cams when an end of the ribbon is approached and to arrest the movement of the engaged cam with the shaft, and means controlled by the movement of the shaft for disengaging the arresting means after the reversal in the direction of the feed of the ribbon has been effected.

46. In a type-writing machine, the combination of a power-driven carriage, a shaft adapted to be turned by the power which moves the carriage, a groove in said shaft, ribbon-spools

loosely mounted on said shaft, means for connecting either ribbon-spool to rotate with the shaft, a bar contained within the groove in the shaft and controlling the said connecting means, reversing-cams that are adapted to rotate with the shaft and control the movement of the bar in said groove, and independently and automatically operable arresting devices that are controlled by the amount of ribbon on either spool and which coöperate with the reversing-cams to arrest them and thereby effect an automatic movement of the bar in the groove during the continued rotation of the shaft.

47. In a type-writing machine, the combination of a power-driven carriage, a shaft adapted to be turned by the power which moves the carriage and which has therein a groove, ribbon-spools loosely mounted on said shaft, means for connecting either ribbon-spool to rotate with the shaft, a bar contained within the groove in the shaft and controlling the said connecting means, reversing-cams that are adapted to rotate with the shaft and control the movement of the bar in said groove, independently and automatically operable arresting devices that are controlled by the amount of ribbon on either spool and which coöperate with the reversing-cams to arrest them and thereby effect an automatic movement of the bar in the groove during the continued rotation of the shaft, and releasing-cams which are fixed to rotate with the shaft and automatically disengage an arresting device after the shift of the bar in its groove has been effected.

48. In a type-writing machine, the combination of a power-driven carriage, a shaft adapted to be turned by the power which moves the carriage, a groove in said shaft, ribbon-spools loosely mounted on said shaft, a pawl for connecting either ribbon-spool to rotate with the shaft, a bar contained within the groove in the shaft and controlling the said pawl, reversing-cams that are adapted to rotate with the shaft and control the movement of the bar in said groove, independent arresting-arms, each having independently-operable means connected thereto that is adapted to bear on the outer surface of the ribbon on a spool to automatically control the position of the associated arresting-arm, said arresting-arms coöoperating with the reversing-cams to arrest them and thereby effect an automatic movement of the bar in the groove during the continued rotation of the shaft, releasing-cams which are fixed to rotate with the shaft and automatically disengage an arresting-arm after the shift of the bar in its groove has been effected, and hand-operated means for turning said shaft.

49. In a type-writing machine, the combination of ribbon-spools, reversing devices therefor, and cams that are adapted to assume different positions relative to said reversing de-

5 vices and which in one position of each cam relative to its associated reversing device will prevent the reversing actuation of the latter and in another position relative to its associated cam will afford a reversing operation.

10 50. In a type-writing machine, the combination of ribbon-spools, reversing devices therefor, and cams which are adapted to rotate with said reversing devices or independently thereof.

15 51. In a type-writing machine, the combination of ribbon-spools, reversing devices therefor, means controlled by said reversing devices for affording a change in the direction of the feed of the ribbon, cams which are adapted to move with said reversing devices or to move independently thereof, and means for automatically effecting a relative movement between said cams and reversing devices.

20 52. In a type-writing machine, the combination of ribbon-spools, reversing devices therefor, means controlled by said reversing devices for affording a change in the direction of the feed of the ribbon, cams which are adapted to rotate with said reversing devices or to rotate independently thereof, and means for automatically arresting the reversing devices to effect a relative movement between said cams and reversing devices to automatically change the direction of the feed of the ribbon and set the parts for the next reversing operation.

25 53. In a type-writing machine, the combination of reversing devices for effecting a change in the direction of the feed of the ribbon and which are adapted to receive a movement relatively to each other, and means coöperating therewith to automatically set the parts for the next reversing operation when they are actuated to effect a reversal in the direction of the feed of the ribbon.

30 54. In a type-writing machine, the combination of ribbon-spools, reversing devices therefor, abutments carried by said reversing devices, automatically-actuated arresting devices coöperating with said abutments to prevent a movement of a reversing device, and means for automatically controlling the engagement and disengagement between the arresting devices and said abutments.

35 55. In a type-writing machine, the combination of ribbon-spools, reversing devices therefor, abutments carried by said reversing devices, automatically-actuated arresting devices coöperating with said abutments to prevent a movement of a reversing device, and cams which are adapted to rotate with or independently of said reversing devices for automatically controlling the engagement and disengagement between the arresting devices and said abutments.

40 56. In a type-writing machine, the combination of ribbon-spools, reversing devices therefor, abutments carried by said reversing de-

5 vices, means for maintaining the abutments on the different reversing devices at an angle one to another, and automatically-actuated means for arresting said abutments.

70 57. In a type-writing machine, the combination of ribbon-spools, reversing devices therefor, abutments carried by said reversing devices, means for maintaining the abutments on the different reversing devices at an angle one to another, automatically-actuated means for arresting said abutments, and means for automatically controlling the engagement and disengagement between the arresting means and said abutments.

75 58. In a type-writing machine, the combination of ribbon-spools, reversing devices therefor and which are adapted to rotate as the ribbon-spools turn, abutments carried by said reversing devices, means for automatically shifting said reversing devices so that the abutments on the different reversing devices will project at an angle one to another, and automatically-actuated arresting means coöperating with said abutments.

80 59. In a type-writing machine, the combination of ribbon-spools, reversing devices therefor and which are adapted to rotate as the ribbon-spools turn, abutments carried by said reversing devices, means for automatically shifting said reversing devices so that the abutments on the different reversing devices will project at an angle one to another, automatically-actuated arresting means coöperating with said abutments, and cams which are differently disposed and one of which coöperates with the abutments of each reversing device, one of said cams affording an engagement between abutments of its associated reversing device and the arresting means when the other cam prevents such an engagement between the abutments of its associated reversing device and the arresting means.

85 60. In a type-writing machine, the combination of ribbon-spools, reversing devices therefor, abutments on said reversing devices, elliptical cams, and means for positioning the abutments on one reversing device at an angle to the length of the associated cam when the abutments on the other reversing device are substantially coincident with the length of the associated cam, and arresting means which coöperate with said abutments.

90 61. In a type-writing machine, the combination of ribbon-spools, a shaft therefor, means for connecting either ribbon-spool to said shaft, reversing devices operatively connected to said connecting means, abutments on said reversing devices, elliptical cams, means for positioning the abutments of one reversing device at an angle to the length of the associated cam when the abutments on the other reversing device are substantially coincident with the length of the associated cam, and automatically-actuated arresting means which coöperate with said abutments.

62. In a type-writing machine, the combination of ribbon-spools, a shaft therefor, means for connecting either ribbon-spool to said shaft, reversing devices operatively connected to said connecting means, a bar that moves longitudinally of said shaft and is connected to said reversing devices, abutments on said reversing devices, elliptical cams, means controlled by said bar for affording a positioning of the abutments on one reversing device at an angle to the length of the associated cam when the abutments on the other reversing device are substantially coincident with the length of the associated cam, and automatically-actuated arresting means which coöperate with said abutments.

63. In a type-writing machine, the combination of ribbon-spools, a shaft, reversing devices, means for arresting said reversing devices and controlling-cams, said ribbon-spools, reversing devices and controlling-cams being carried by and adapted to rotate with said shaft.

64. In a type-writing machine, the combination of a shaft, ribbon-spools, reversing-cams, engaging means controlled by said cams and adapted to connect either spool to rotate with the shaft, arresting devices, one for each reversing-cam, and controlling-cams, said ribbon-spools, reversing-cams, engaging means and controlling-cams being mounted on and adapted to rotate with said shaft.

65. In a type-writing machine, the combination of a ribbon-vibrator, means for automatically moving said ribbon-vibrator to and from the printing-point, and means for affording a further independent movement of said ribbon-vibrator away from the platen.

66. In a type-writing machine, the combination of a pivoted ribbon-vibrator, means for automatically moving said ribbon-vibrator to and from the printing-point, and means for affording a further independent movement of said ribbon-vibrator on its pivot.

67. In a type-writing machine, the combination of a ribbon-vibrator, means for automatically moving said ribbon-vibrator to and from the printing-point, and spring-pressed means for affording a further independent movement of said ribbon-vibrator away from the platen in order to give better access to the printing-line.

68. In a type-writing machine, the combination of a ribbon-vibrator, a rock-shaft on which said vibrator is carried, means for rocking said rock-shaft, and spring-pressed means for normally maintaining a fixed relation between the vibrator and rock-shaft and for permitting when desired an independent movement of the vibrator against the tension of its spring-pressed means.

69. In a type-writing machine, the combination of a vibratory device, a ribbon-vibrator carried by said vibratory device and adapted to move independently thereof, and means for

normally maintaining a fixed relation between said ribbon-vibrator and its vibratory device.

70. In a type-writing machine, the combination of a rock-shaft, a ribbon-vibrator carried by said shaft and movable independently thereof, means for rocking said shaft to move the vibrator to and away from the printing-point, a stop device on the rock-shaft, a coöperating stop device on the vibrator, and a spring which tends to maintain a fixed relation between said vibrator and shaft but permits an independent movement of the vibrator relative to the shaft.

71. In a type-writing machine, the combination with escapement mechanism, of a rock-shaft therefor, and a ribbon-vibrator connected to said rock-shaft so as to move with the rock-shaft or independently thereof.

72. In a type-writing machine, the combination with escapement mechanism, a rock-shaft to which one member of the escapement mechanism is directly connected, a ribbon-vibrator directly connected to and carried by said rock-shaft, and means for rocking said shaft.

73. In a type-writing machine, the combination of a rock-shaft, feed-dogs directly connected to said rock-shaft, escapement devices which coöperate with said feed-dogs, a ribbon-vibrator carried directly by said rock-shaft and adapted to be moved thereby toward and away from the printing-point, and means for rocking said shaft.

74. In a type-writing machine, the combination of reversing means for effecting a change in the direction of the feed of the ribbon, and means coöperating therewith to automatically arrest a portion of said reversing means and thereby cause a reversal in the feed of the ribbon and to automatically set the parts for the next reversing operation.

75. In a type-writing machine, the combination of ribbon-spools, reversing means therefor, abutments carried by said reversing means and maintained at angles to one another, and automatically-actuated means for arresting said abutments.

76. In a type-writing machine, the combination of a platen, a ribbon-vibrator, means for automatically moving said vibrator to and from the printing-point, and means independent of the automatically-actuated moving means for affording a movement of the vibrator away from the platen in order to give better access to the printing-line.

77. In a type-writing machine, the combination of ribbon-spools, means for connecting either ribbon-spool with its driving means, a cam which normally is adapted to rotate in unison with said ribbon-spools and controls said connecting means, and means for automatically arresting said cam when an end of the ribbon is reached.

78. In a type-writing machine, the combination of ribbon-spools, a controlling device which normally rotates as the ribbon-spools are rotated, and means which automatically

afford a stopping of said device when an end of the ribbon is reached, to effect a reversal in the direction of the feed of the ribbon.

79. In a type-writing machine, the combination of ribbon-spools, a reversing device which is adapted to receive a continuous rotation in unison with the ribbon-spools or to remain fixed against movement during the rotation of the spools, and means for automatically effecting an arrest of said reversing device.

80. In a type-writing machine, the combination of ribbon-spools, a reversing device which is adapted to rotate in unison with the ribbon-spools or to remain fixed against movement during the rotation of the spools, and means controlled by the ribbon for arresting said reversing device when an end of the ribbon is reached and thereby effect a reversal in the direction of the feed of the ribbon.

81. In a type-writing machine, the combination of ribbon-spools, a reversing device which is adapted normally to rotate with the ribbon-spools, means controlled by said reversing device when it is brought to rest during the feed of the ribbon for effecting a connection between one ribbon - spool and its driving means and for simultaneously effecting a disconnection between the other spool and its driving means, and means for effecting an arrest of the reversing device when an end of the ribbon is reached.

Signed at Syracuse, in the county of Onondaga and State of New York, this 14th day of October, A. D. 1902.

ALEXANDER T. BROWN.
